UNITED STATES PATENT OFFICE.

ERIC C. ALLEN, OF ASHLAND, ALABAMA.

ADVERTISING DEVICE.

Application filed March 26, 1921. Serial No. 455,759.

To all whom it may concern:

Be it known that I, ERIC C. ALLEN, a citizen of the United States, residing at Ashland, in the county of Clay and State of Alabama, have invented certain new and useful Improvements in Advertising Devices, of which the following is a specification.

The invention relates to improvements in advertising devices, and more particularly to a mechanically operated type of the same.

The principal object of the invention is to provide for a device of the character mentioned, and one having the configuration of a human figure and embodying an internal mechanism, whereby to effect a realistic simulation of a man or woman in the act of smoking a pipe, cigar, cigarette or the like, either for the advertising of any particular make or brand of pipe, cigar, cigarette, or smoking tobacco, or medical remedies, such as are generally smoked and inhaled for the treatment of catarrhal affections; or, in its more practical use, for effecting the burning of tobacco in new pipes, whereby to eliminate or otherwise prevent the usual irritation of the tongue of a smoker, such as occurs in the initial use of new pipes.

With the foregoing and other objects in view, the invention resides in the certain novel and useful construction and arrangement of parts as will be hereinafter more fully described, set forth in the appended claims, and illustrated in the accompanying drawing, in which:—

Figure 1 is a vertical section through the body or casing of the device showing the arrangement of the mechanism therein,

Fig. 2 is a plan view of the operating mechanism per se,

Fig. 3 is an enlarged detail of the control or check valve and its connection,

Fig. 4 is a sectional view taken on the line 4—4 of Fig. 3, looking in the direction of the arrow, and,

Fig. 5 is a similar view to that of Fig. 4 but looking in the opposite direction of the arrow.

Referring to the drawing, wherein similar characters of reference designate corresponding parts in the several views thereof, the numeral 10 indicates generally the hollow body or casing of the device, which is preferably formed of either cast or sheet

metal, having the configuration of a human being, or the bust and connected head portion of a human being, as may be desired, and the mouth portion of the dummy head 60 is arranged to have its lip portions inturned, as at 12, or otherwise suitably formed for the insertion therein of a pipe or the like 13, as shown.

Connecting the inner end of the pipe stem, 65 or other device to be smoked, is an inlet tube 14 leading to an inlet 15, Fig. 5, of a valve casing 16 which has its interior divided by a partition wall 17 rising from the bottom wall thereof for a major portion of 70 the height of the same, and a second partition wall 18 depending from the top wall of the casing for a distance below the plane of the upper edge of the partition wall 17, whereby to provide a tortuous passage extending between the opposed walls of the partitions and their opposite walls and the opposed walls of the casing 16. Formed in the leg of the passage-way 75 between the partition 17 and the opposed walls of the casing 16 at a point above the inlet port 15 is a valve seat 19 adapted for supporting thereon a ball valve 20, and a similarly formed valve seat 21 is arranged at the lower end of the partition wall 18, 80 between the same and the opposed wall of the casing 16, for the seating thereon of a second ball valve 22 which normally closes the complementary leg of the said passage-way. Leading from the legs of the passage 85 enclosed by the ball valve 22 is a discharge port 23 which opens into a tube 24 which extends to and has its outer end positioned between the lip 11 immediately adjacent the pipe stem 13, or the tube may lead to the 90 nasal outlet to the nose portion of the casing; as is shown in dotted lines in Fig. 1, or, if desired, the tube can be arranged to simultaneously discharge outwardly of openings 95 formed in both the mouth and the nose portion of the head of the dummy casing.

Opening centrally of the side wall of the casing 16 opposite to that in which the ports 15 and 23 are formed is a port 25 to which is connected a tube 26 leading to a bellows 27 100 which is suitably supported in position within the head portion of the dummy or casing 10, preferably in a plane horizontally thereof and in alinement with the valve casing 16 and the mouth 12 of the casing. The bellows 27 is provided with a rearwardly extending arm 28 by means of which it is to be 110

operably connected to a power means of any known type suitable for the purpose, a preferred form of the same to be hereinafter fully described, and it is normally held in its inoperative or contracted positions by means of a coiled spring 29 which has one end connecting the arm 28 and its other end suitably connected to the wall of the casing 10.

- 10 For operating the bellows 27, the free end of the arm 28 is pivotally connected to the upper end of an actuating rod 30 which has its lower end pivotally engaged in a bifurcation 31 formed medially in the free end 15 edge of a power lever 32 which is, in turn, pivoted at its other end with bracket arms 33 formed with or supported inwardly of the front wall of the lower portion of the dummy casing 10. The lever 32 is substantially T-shaped in plan, and has the bifurcation 31 formed in the free end edge of the T head thereof, and the opposite offset portions of the T-head constitute track-ways each disposed in the path of pairs of rollers 34 spaced at diametrically opposite points on and correspondingly of the opposed faces of a pair of discs or wheels 35 and 36, which are mounted on a shaft 37 journaled at its opposite ends in the side wall of the casing 20 10, the discs or wheels 35 and 36 being disposed to each side of the lever 32 and rotating in planes parallel thereto. Mounted on the shaft 37 immediately to one side of the disc or wheel 35 is a pinion 38 which is arranged in mesh with a gear 39 carried at one 25 end of a shaft 40 upon which is normally wound a cord or cable 41, the free end of which depends into the lower portion of the casing 10 and has a weight 42 secured thereto, while to the outer side of the disc or 30 wheel 36 is a second gear 43, on the shaft 37, and in meshing relation with a pinion 44 carried on a shaft 45 upon which is secured a fly wheel 46. The shafts 40 and 45 35 are suitably journaled in the walls of the casing 10, or in brackets carried inwardly of the latter. This weight 42 constitutes the power means of the apparatus, and, when released from its raised position, gravitates 40 in the downward direction of the casing 10 to unwind the cord or cable 41 for imparting motion to the mechanism. In lieu of the foregoing weight motor mechanism, the shaft 40 may be suitably driven from a 45 spring, electric or other form of power device.

In the operation of the device, a pipe, cigar or the like is inserted between the lips 12, and is lighted upon the starting up of the 50 mechanism, the initial movement of which forces down on the lever 32, by reason of certain of the rollers 34 moving into contact with the track-ways thereof during the rotation of the discs or wheels 35 and 36, 55 which, in turn, pulls downward on the rod

30 and the lower movable portion of the bellows 27 against the tension of the coiled spring 29. The suction created by the opening movement of the bellows 27 acts to raise the ball valve 20 and draws smoke from the 50 pipe 13 through the tube 14, the port 15, the valve seat 19, the port 25, the tube 26 and into the bellows 27, and upon the closing movement of the bellows 27, under the tension of the contacting action of the spring 55 29, the smoke is returned through the tube 26 to the port 25, into the center portion of the valve casing 16, and is forced past the ball valve 22 through the valve seat 21, and outward of the port 23 to the tube 24 and 60 so thence to atmosphere through the lips 12, or the nose, or both as the case may be. Continued operation of the power mechanism will repeat this cycle of operation until the tobacco or other burning material has been 65 entirely consumed.

It is to be understood that, while the construction and arrangement of the parts of the invention have been set forth herein in specific details, various changes in the size, shape, and assembly of such parts may be resorted to without departing from the spirit and scope thereof.

Having thus fully described the invention, what is claimed, is:—

1. In a device for the purpose set forth, a hollow body provided with an opening for the insertion therein of a cigar, cigarette or pipe containing tobacco to be consumed by the smoking thereof, and further provided with an eduction outlet for the smoke, a valve casing within said body and having an inlet communicating with said inlet and a discharge port communicating with said outlet, a bellows within said body and provided with a combined inlet and discharge tube opening into the casing, valves within said casing for controlling the ingress and egress of the smoke derived from the actual consumption of the article through the operation of said bellows, and a power operated mechanism wholly within said body for actuating said bellows to cause the consumption of the article whereby the smoke derived from the latter will be inducted and educted during the operation of the bellows.

2. In a device for the purpose set forth, a hollow body provided with an opening for the insertion therein of a cigar, cigarette or pipe containing tobacco to be consumed by the smoking thereof, and further provided with an eduction outlet for the smoke, a valve casing within said body and having an inlet communicating with said inlet and a discharge port communicating with said outlet, a bellows within said body and provided with a combined inlet and discharge tube opening into the casing, valves within said casing for controlling the ingress and egress of the smoke derived from the actual con-

sumption of the article through the operation of said bellows, a spring controlled arm projecting rearwardly from the bellows, an actuating rod connected therewith, and a power operated mechanism arranged wholly within said body for actuating said bellows to cause the consumption of the article whereby the smoke derived from the latter will be inducted and educted during the operation of the bellows.

3. In a device for the purpose set forth, a hollow body provided with an opening for the insertion therein of a cigar, cigarette or pipe containing tobacco to be consumed by the smoking thereof and further provided with an eduction outlet for the smoke, a valve casing within said body and having an inlet communicating with said opening, and a discharge port communicating with said outlet, a bellows within said body and provided with a combined inlet and discharge tube opening into the casing, valves within said casing for controlling the ingress and egress of the smoke derived from the actual consumption of the article through the operation of said bellows, a power operated mechanism wholly within said body for actuating said bellows to cause the consumption of the article whereby the

smoke derived from the latter will be inducted and educted during the operation of the bellows, the inlet of said casing arranged out of alinement with respect to the discharge ports of the casing, and said combined inlet and discharge tube opening into said casing medially thereof.

4. In a device for the purpose set forth a hollow body provided with an opening for the insertion therein of a cigar, cigarette or pipe containing tobacco to be consumed by the smoking thereof and further provided with an eduction outlet for the smoke, a valve casing within said body and having an inlet communicating with said opening and a discharge port opening into said outlet, a spring controlled bellows within the body and communicating with said casing, valves within said casing for controlling the ingress and egress of smoke derived from the actual consumption of the article through the operation of said bellows, and a power operated mechanism within said body and connected with the bellows and actuating it to cause the consumption of the article.

In testimony whereof, I affix my signature hereto.

ERIC C. ALLEN.
